SUNSHADE ATTACHMENT FOR A PAIR OF SPECTACLES OR THE LIKE

Steve Boxer, 4414 Woodman Ave., Sherman Oaks, Calif.
91403, and Norman C. Bouse, 1655 Chelsea Road, San
Marino, Calif. 91108

Original design application Oct. 4, 1965, Ser. No. 87,296,
now Patent No. 206,352, dated Nov. 29, 1966. Divided
and this application Apr. 11, 1966, Ser. No. 3,419

Term of patent 14 years

(Cl. D57—1)

FIG. 1.

FIG. 2.

FIG. 3.

FIG. 4.

FIG. 5.

FIGURE 1 is a front elevational view of the sunshade attachment for a pair of spectacles or the like showing our new design.

FIGURE 2 is a side elevational view thereof.

FIGURE 3 is a top plan view thereof.

FIGURE 4 is a rear elevational view thereof.

FIGURE 5 is a front perspective view thereof.

The broken line showing of the spectacle frame of the drawing, partially omitted in FIGURE 3, is for illustrative purposes only.

This application is a division of my copending application Ser. No. 87,296, filed Oct. 4, 1965, now Patent No. D. 206,352, issued Nov. 29, 1966.

We claim:

The ornamental design for a sunshade attachment for

a pair of spectacles or the like, substantially as shown and described.
